LAMP

Wesley L. Thomas, 109 S. Catalina St., Los Angeles,
Calif. 90004, and James Allan Thomas, 861 Willow
Drive, Brea, Calif. 92621

Filed Apr. 30, 1973, Ser. No. 355,558

Term of patent 14 years

Int. Cl. D26—05

U.S. Cl. D48—20 R

FIG. 1 is a front perspective view of a lamp showing our new design; and

FIG. 2 is a bottom view of the lamp.

The side of the lamp opposite to that shown in FIG. 1 is identical to the disclosed side.

We claim:

The ornamental design for a lamp, substantially as shown.
